UNITED STATES PATENT OFFICE.

NOEL PEMBERTON-BILLING, OF HERTFORD, ENGLAND.

DOMESTIC HEATING AND COOKING APPARATUS.

1,345,400.

Specification of Letters Patent.

Patented July 6, 1920.

Application filed July 23, 1919. Serial No. 312,852.

To all whom it may concern:

Be it known that I, NOEL PEMBERTON-BILLING, M. P., a subject of the King of England, residing at Hertford, in the county of Hertford, England, have invented certain new and useful Improvements in Domestic Heating and Cooking Apparatus, of which the following is a specification.

This invention relates to an improved construction of domestic heating- and cooking-apparatus of the type in which a single shaft contains a fire which may be utilized to serve two or more dwelling-rooms. Constructions have previously been suggested in which a single shaft communicates with fire-place openings situated one in each of several rooms, the shaft containing two grates separated from one another by a vertical backing, and the grates and backing being mounted on a revolving support so that the fire in one of the grates can be turned to be exposed through any one of the fire-place openings around the shaft.

The improved construction of heating- and cooking-apparatus according to the present invention, comprises a column or chimney-shaft around which a plurality of dwelling-rooms is set, (the said shaft being preferably at a meeting of the angles of different rooms), and having a plurality of fire-place openings in the sides of it, with the sills of all the openings at or about at the same level, the said column having in it at or near the level of the sills, a single grate, the entire surface of which serves all the fire-place openings.

Preferably there are provided vertical webs at opposite sides of each fire-place opening, and radially to the shaft, so that the faces of the webs constitute reveals for each opening, doors on vertical hinges for some or all of the said fire-place openings, and covers hinged to the reveals by vertical hinges.

According to one modification in addition to the vertical webs and outwardly opening doors for some of the openings, there are provided for another of said openings, (e. g. that opening which faces a kitchen) an outwardly-opening plate on a horizontal hinge, and an inwardly-opening grid on a horizontal hinge, both the plate and the grid having their hinges at or about the sill level, and covers hinged to the reveals by

vertical hinges. These covers form facings 55 behind each of which one of the vertically hinged doors, while open, can be concealed. The covers aforesaid are preferably ornamental and by their use the inner or discolored face of the open doors is kept out of 60 sight.

Below the level of the sills is preferably a water-tube forming a horizontal frame which supports a fire-grate; uptake and downcomer pipes rise from the water-tube 65 frame, and at the upper end of said pipes is a hot-water tank in the flue.

The hot-water tank, a heating chamber with an open front, ovens, and a smoke-box are above the level of the aforesaid fire-place openings into the rooms and are supported by the column aforesaid and also are upheld by posts extending up from the floor of the building.

In the accompanying drawings— 75

Figure 1 is a vertical central section through a heating- and cooking-device according to the present invention;

Fig. 2 is a plan of the same in section on the line 2—2 of Fig. 1, and 80

Fig. 3 is a diagrammatic view showing the arrangement of the hot-water tank, the ovens, and the heating-chamber and indicating the course of the draft around them.

With reference first to Figs. 1 and 2, CS 85 is the column forming as aforesaid the lower part of a chimney-shaft which column has in it four fire-place openings numbered 1, 2 90 3, 4, respectively, in its sides. The opening 4 is assumed to be the opening into a kitchen, 90 the other openings being allotted each of them to some other one in a plurality of dwelling-rooms set around the chimney shaft and including the kitchen. The sills 95 of all the openings are at about the same level. In the illustrated example the column and shaft are central in a group of four rooms W, X, Y, Z, set around it, Z being the kitchen. Vertical webs VW¹, VW², VW³, VW⁴ radiate from the shaft and their faces 100 F constitute reveals for each opening 1, 2, 3 or 4. As to the openings 1, 2 and 3, there is an outwardly-opening door D¹, D² or D³ for each of them, hinged on vertical hinges V¹ or V² or V³ at one side of the corresponding 105 opening. These doors, which can have mica panes, are used to close the openings, and when they are closed, the draft or air supply

for the fire can pass into the stove only by way of a bottom chamber BC which is part of, or which encircles, the stove base, and has ventilating valves VV in it.

- 5 Covers C¹, C², C³ are hinged by vertical hinges to the outer margins of the reveals and the door of any of the openings, for instance the door D¹, can be opened out against the reveal and concealed (see the door D³ in 10 Fig. 2) by the corresponding cover C³ when it is desired that the opening 3 should be wide open.

As to the opening 4 into the kitchen, there is hinged to it, on a horizontal hinge 15 at the level of the sill, a plate P and a grid G. The plate P when turned up (as in chain-line in Fig. 1) serves as a door to close the opening 4 and the grid G can stand upright behind the door, as shown in 20 full-line in Fig. 1; when desired, the door can be opened out horizontally and supported in that position by vertical legs L which, being hinged at their upper ends to the door, gravitate automatically into position, when the plate descends, so as to support it horizontally, as shown in Fig. 1. This plate serves as a hob for dishes and 25 cooking utensils. The grid G can also be downturned about its hinge (see chain-lines 30 in Fig. 1), in which case it extends on the same level as that of the down-turned plate P inward across the main fire which is below it, as will hereinafter appear. A supplementary fire, such as a fire of wood, can 35 be placed upon this grid above the main fire if desired.

Below the level of the sills is a water-tube WT in the form of a square frame; this supports a fire-grate FG upon which 40 the main fire is carried. Uptake and down-comer pipes P¹ P² rise from the water-tube frame and at the upper ends are connected to a hot-water tank HWT from which bath and kitchen supplies can be drawn.

- 45 Above the level of the tops of the openings 1, 2, 3 and 4 (see Figs. 1 and 3) are ovens O¹, O², O³, a heating-chamber HC with an open front and the hot-water tank HWT, together with a smoke-box SB from 50 which a smoke-tube ST extends up the chimney-shaft. The ovens, the heating-chamber, and the hot-water tank and smoke-box are castings supported by the column CS and the posts w, x, y, z. There are draft flues DF extending between and around them, as shown in Fig. 3, and four dampers DR, three of which are diagrammatically shown in Fig. 3, to regulate the path of the draft through the flues, by cutting out that 55 one of the paths in which they are placed. Access of air to the fire-grate FG when desired is obtained by way of the hollow bottom chamber BC having in the side of it air-openings in which are the ventilating valves VV of a well-known type for regu-

lating the passage of air therethrough. In the bottom chamber BC is the ash-drawer AD.

What I claim as my invention and desire to secure by Letters Patent is:

1. Domestic heating-apparatus comprising the combination of a hollow column or chimney shaft around which a plurality of dwelling-rooms is set, (the said shaft being preferably at a meeting of the angles of different rooms), a plurality of fire-place openings in the sides of the column with the sills of all the openings substantially at the same level, a single grate in the said column at substantially the level of the sills, the entire surface of which grate serves all the fire-place openings, vertical webs at the opposite sides of each opening and radial to the shaft, so that the faces of the webs constitute reveals for each opening, and outwardly opening doors on vertical hinges for at least one of the said openings.

2. Domestic heating-apparatus comprising the combination of a hollow column or chimney-shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, vertical webs at the opposite sides of each opening and radial to the shaft, so that the faces of the webs constitute reveals for each opening, and covers hinged to the reveals at substantially their outer margins by vertical hinges.

3. Domestic heating-apparatus comprising the combination of a hollow column or chimney shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, vertical webs at the opposite sides of each opening and radial to the shaft, so that the faces of the webs constitute reveals for each opening, outwardly opening doors on vertical hinges for at least one of the said openings and covers hinged to the reveals at substantially their outer margins by vertical hinges.

4. Domestic heating-apparatus comprising the combination of a hollow column or chimney-shaft, around which a plurality of dwelling rooms is set, (the said shaft being preferably at a meeting of the angles of different rooms), a plurality of fire-place openings in the sides of the column with the

sills of all the openings at substantially the same level, a single grate in the said column at substantially the level of the sills, the entire surface of which grate serves all 5 the fire-place openings, vertical webs at the opposite sides of each opening and radial to the shaft, so that the faces of the webs constitute reveals for each opening, an outwardly opening plate on a horizontal hinge 70 and an inwardly opening grid on a horizontal hinge, both plate and grid being hinged at substantially the sill level for another of said openings. 10

5. Domestic heating-apparatus comprising the combination of a hollow column or chimney shaft around which a plurality of dwelling rooms is set, (the said shaft being preferably at a meeting of the angles of different rooms), a plurality of fire-place openings in the side of the column with the sills of all the openings at substantially the same level, a single grate in the said column at substantially the level of the sills, the entire surface of which grate serves all the 15 fire-place openings, vertical webs at the opposite sides of each opening and radial to the shaft so that the faces of the webs constitute reveals for each opening, outwardly opening doors on vertical hinges for some 20 of the said openings, an outwardly opening plate on a horizontal hinge and an inwardly opening grid on a horizontal hinge, both plate and grid being hinged at substantially the sill level of another of said openings. 25

35. 6. Domestic heating-apparatus comprising the combination of a hollow column or chimney-shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire 40 surface of which grate serves all the fire-place openings, vertical webs at the opposite sides of each opening and radial to the shaft, so that the faces of the webs constitute reveals for each opening, covers hinged 45 to the reveals at or near their outer margins by vertical hinges, an outwardly opening plate on a horizontal hinge and an inwardly opening grid on a horizontal hinge, both plate and grid being hinged at substantially 50 the sill level for another of said openings. 55

7. Domestic heating-apparatus comprising the combination of a hollow column or chimney shaft around which a plurality of dwelling-rooms is set, (the said shaft being 60 preferably at a meeting of the angles of different rooms), a plurality of fire-place openings in the sides of the column with the sills of all the openings at substantially the same level, a single grate in the said column at substantially 65 the level of the sills, the entire

surface of which grate serves all the fire-place openings, vertical webs at the opposite sides of each opening and radial to the shaft, so that the faces of the webs constitute reveals for each opening, outwardly opening doors on vertical hinges for some of the said 70 openings, an outwardly opening plate on a horizontal hinge, and an inwardly-opening grid on a horizontal hinge both plate and grid being hinged at substantially the sill level for another of said openings, and covers hinged to the reveals at or near their outer margins by vertical hinges. 75

8. Domestic heating-apparatus comprising the combination of a hollow column or chimney-shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, and a water-tube frame 80 below the level of said sills which supports a fire-grate and has uptake and downcomer pipes rising from it, and, at the upper ends of said pipes, a hot water tank. 85

9. Domestic heating-apparatus comprising the combination of a hollow column or chimney shaft around which a plurality of dwelling-rooms is set, (the said shaft being preferably at a meeting of the angles of different rooms), a plurality of fire-place openings 90 in the sides of the column with the sills of all the openings at substantially the same level, a single grate in the said column at substantially the level of the sills, the entire surface of which grate serves all the fire-place openings, vertical webs at the opposite sides of each opening and radial to the shaft, so that the faces of the webs constitute reveals for each opening, outwardly opening doors on vertical hinges for at least one of 100 the said openings, covers hinged to the reveals at substantially their outer margins by vertical hinges, and a water tube frame below the level of said sills which supports a fire-grate and has uptake and downcomer pipes rising from it and, at the upper ends of said pipes, a hot water tank. 105

10. Domestic heating-apparatus comprising the combination of a hollow column or chimney shaft around which a plurality of dwelling-rooms is set, (the said shaft being preferably at a meeting of the angles of different rooms), a plurality of fire-place openings in the sides of the column with the sills of all the openings at substantially 120 the same level, a single grate in the said column at substantially the level of the sills, the entire surface of which grate serves all the fire-place openings, vertical webs at 125 the opposite sides of each opening and ra- 130

dial to the shaft, so that the faces of the webs constitute reveals for each opening, outwardly opening doors on vertical hinges for some of the said openings, an outwardly opening plate on a horizontal hinge, an inwardly-opening grid on a horizontal hinge, both plate and grid being hinged at substantially the sills' level for another of said openings, covers hinged to the reveals at substantially their outer margins by vertical hinges and a water-tube frame below the level of said sills which supports a fire-grate and has uptake and downcomer pipes rising from it and, at the upper ends of said pipes, a hot water tank.

11. Domestic heating-apparatus comprising the combination of a hollow column or chimney-shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, and an oven or ovens, a heating-chamber with an open front, a hot water tank, draft flues and a smoke-box, all above the level of the aforesaid openings.

12. Domestic heating-apparatus comprising the combination of a hollow column or chimney shaft around which a plurality of dwelling-rooms is set, (the said shaft being preferably at a meeting of the angles of different rooms), a plurality of fire-place openings in the side of it with the sills of all the openings at substantially the same level, a single grate in the said column at substantially the level of the sills, the entire surface of which grate serves all the fire-place openings, vertical webs at the opposite sides of each opening and radial to the shaft, so that the faces of the webs constitute reveals for each opening, outwardly opening doors on vertical hinges for at least one of the said openings, covers hinged to the reveals at substantially their outer margins by vertical hinges, and an oven, a heating chamber with an open front, a hot water tank, draft flues and a smoke box, all above the level of the aforesaid openings.

13. Domestic heating-apparatus comprising the combination of a hollow column or chimney shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, vertical webs at the opposite sides of each opening and radial

to the shaft, so that the faces of the webs constitute reveals for each opening, outwardly opening doors on vertical hinges for some of the said openings, an outwardly opening plate on a horizontal hinge, an inwardly-opening grid on a horizontal hinge, both plate and grid being hinged at substantially the sill level for another of said openings, covers hinged to the reveals at substantially their outer margins by vertical hinges, and an oven, a heating-chamber with an open front, a hot water tank, draft flues and a smoke-box, all above the level of the aforesaid openings.

14. Domestic heating-apparatus comprising the combination of a hollow column or chimney-shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, a water-tube frame below the level of said sills which supports a fire-grate and has uptake and downcomer pipes rising from it, and, at the upper ends of said pipes, a hot water tank, and an oven, a heating-chamber with an open front, a hot water tank, draft flues and a smoke box, all above the level of the aforesaid openings.

15. Domestic heating-apparatus comprising the combination of a hollow column or chimney shaft around which a plurality of dwelling-rooms is set, (the said shaft being preferably at a meeting of the angles of different rooms), a plurality of fire-place openings in the sides of the column with the sills of all the openings at substantially the same level, a single grate in the said column at substantially the level of the sills, the entire surface of which grate serves all the fire-place openings, vertical webs at the opposite sides of each opening and radial to the shaft, so that the faces of the webs constitute reveals for each opening, outwardly opening doors on vertical hinges for at least one of the said openings, covers hinged to the reveals at substantially their outer margins by vertical hinges, a water-tube frame below the level of said sills which supports a fire-grate and has uptake and downcomer pipes rising from it and, at the upper ends of said pipes, a hot water tank, and an oven, a heating chamber with an open front, a hot water tank, draft flues and a smoke box, all above the level of the aforesaid openings.

16. Domestic heating-apparatus comprising the combination of a hollow column or chimney shaft around which a plurality of dwelling-rooms is set (the said shaft being preferably at a meeting of the angles of different rooms), a plurality of fire-place

openings in the sides of the column with the sills of all the openings at substantially the same level, a single grate in the said column at substantially the level of the sills, the entire surface of which grate serves all the fire-place openings, vertical webs at the opposite sides of each opening and radial to the shaft, so that the faces of the webs constitute reveals for each opening, outwardly 5 opening doors on vertical hinges for some of the said openings, an outwardly opening plate on a horizontal hinge, an inwardly-opening grid on a horizontal hinge, both plate and grid being hinged at substantially 10 the sill level for another of said openings, covers hinged to the reveals at substantially their outer margins by vertical hinges, a water-tube frame below the level of said sills which supports a fire-grate and has uptake 15 and downcomer pipes rising from it and, at the upper ends of said pipes, a hot water tank, and an oven, a heating chamber with an open front, a hot water tank, draft flues and a smoke box all above the level of the 20 25 aforesaid openings.

17. A heating apparatus, comprising a central shaft having a plurality of openings in opposite sides thereof, radially disposed webs extending from the corners of said 30 shaft, and swinging doors for certain of said openings adapted to extend substantially parallel to and be protected by said webs

when in open position, substantially as described.

18. A heating apparatus, comprising a central shaft having a plurality of openings in opposite sides thereof, radially disposed webs extending from the corners of said shaft, swinging doors for certain of said openings adapted to extend substantially parallel to said webs when in open position, and covers carried by said webs for overlying said doors, substantially as described.

19. A heating apparatus, comprising a central shaft having an opening therein, a vertically swinging plate coöperating with said opening and adapted to be swung downwardly at an angle to the shaft, a mounting therefor adjacent the bottom of the opening, means for supporting said plate when swung downwardly, and a grate adapted to be moved into position across said shaft or into engagement with said plate when in its upper position, substantially as described.

20. A heating apparatus, comprising a rectangular shaft having a plurality of doors therein, and vertical webs extending radially from the corners of said shaft and adapted to coöperate with said doors to protect the same when in open position, substantially as described.

In testimony whereof I affix my signature.

NOEL PEMBERTON-BILLING.
